ROTARY VALVE ENGINE

Wilfred Fred Vallier, Fort Smith, Ark.

Application October 29, 1941, Serial No. 417,031

2 Claims. (Cl. 123—59)

This invention relates to new and useful improvements in internal combustion engines, and more particularly to improvements in rotary valves therefor.

The principal object of the present invention is to provide an improved rotary valve assembly for an internal combustion engine which will permit the exhaust of burnt gases the shortest route possible to eliminate as much as possible the contact of heat to other parts of the engine proper.

Another important object of the invention is to provide rotary valve means in which the intake passageway collars the rotary valve in such a way as to dissipate heat to a high degree.

Another important object of the invention is to provide a rotary valve assembly located at the side of the engine block in such a way that the engine pistons will shut off the rotary valve cylinder ports at the time of firing thereby preventing direct exposure of the rotary valve to the force of combustion.

Various other important objects and advantages of the invention will become apparent to the reader of the following description.

In the drawings:

Figure 1 represents a vertical sectional view through the valve assembly.

Figure 2 is a transverse vertical sectional view.

Figure 3 is a sectional view taken substantially on line 3—3 of Figure 1.

Figure 4 is a fragmentary top plan view of the engine with the conduit removed.

Figure 5 is a fragmentary side elevational view of the engine head.

Referring to the drawings wherein like numerals designate like parts, it can be seen that numeral 5 denotes an engine block preferably having an integral head construction 6. In this block are cylindrical bores 7 in which operate pistons 8 connected by piston rods 9 to a crank shaft 10 operating in a crank case 11. Suitable ignition means 12 is provided at the head of the block 5.

Numerical 13 generally refers to the improved rotary valve assembly and this includes an elongated block 14 which is detachably attached to one side of the cylinder block 5, in a manner so that the ports 15 in one side thereof will match the ports 16 in the opposed side of the block 5.

The valve block 14 has a depending apron 17 formed with openings through which machine screws 18 are disposed and driven into the block 5, and then the block 14 is also provided with a horizontally disposed flange 19 which overlaps the head 6 of the block 5 and has openings through

which machine screws 20 are disposed and driven downwardly into one side edge portion of the head 6.

As can be seen in Figure 2, the block 14 has a longitudinally disposed cylindrical bore 21 containing a rotary valve element which at intervals opposed to the ports 15 is formed with by-passes 22, the back walls of which are cut on a V, as is clearly shown in Figure 2.

Extending upwardly from the bore 21 are ports 23 for exhaust gases. Outwardly of the exhaust ports 23 are intake passageways 24 which extend downwardly and around the lower outside portion of the bore 21 to open into the bore 21 through the bottom thereof, as at 25. Thus, it can be seen that the intake fuel will to a substantial extent tend to dissipate the heat arising from the exhaust of burnt gases through the ports 23.

A conduit 26 is provided on the top of the block 14 and has an exhaust passageway 27 extending longitudinally therein and also an intake passageway 28.

Numerical 29 denotes a tubular support for the rotary valve which extends longitudinally through the bore 21 and has one end disposed into a face plate 30 attached by machine screws or the like 31 to one end of the block 14. Connected to this end of the tubular support 29 is a lubricant pipe 32. A jam nut 33 on this end of the support 29 is driven against the face plate 30 to prevent shifting of the support 29.

The other end of the tubular support 29 is disposed through the upper portion of a housing 34 which extends vertically at the other end of the engine and encases a sprocket chain 35 which is disposed over a sprocket wheel 36 on the crank shaft 10 and also over a sprocket wheel 37 on the corresponding end of the rotary valve (see Fig. 1). A nut 38 is provided on this latter end of the support 29 to prevent longitudinal shifting of the support.

Bushings 40 are provided between the support 29 and the inside of the rotary valve so as to define an oil space 41 to which oil from the interior of the support 29 can pass by way of the openings 42 in said support. At definite and appropriate intervals, the periphery of the rotary valve is formed with circumferential grooves 43 for the reception of oil and radial ports 43' for conducting oil out of said valve.

As can be seen in Figure 1, a pointed valve element 44 is threadedly disposed into the forward end of the support 29 to regulate the passage of oil from the interior of the support 29 to the escape duct 45. Oil that escapes from the

support 29 by way of the duct passes downwardly on the inside of the housing 34, suitably lubricating the chain 35 and ultimately escaping from the housing 34 by way of the port 36 back to the crank case 11.

Attention is directed to the fact that a double oil seal is provided by my invention, one between the wall of the bore 21 and the rotary valve element, and the other in the space 41 between said element and the support 29 and around said support, so that the incoming oil in the support is maintained at a cool temperature to be fed to the exterior of the valve element. Also the oil in the space 41 aids in maintaining the rotary valve element cool.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In an internal combustion engine, a rotary valve assembly including a block, a rotary valve element operative in the block, an elongated tubular support extending through the rotary element, spacer means between the support and the rotary element to define oil spaces, an oil supply to one end of the support, said support having openings therein to permit oil to pass into the said oil spaces.
- 5 2. In an internal combustion engine, a rotary valve assembly including a block, a rotary valve element operative in the block, an elongated tubular support extending through the rotary element, spacer means between the support and the rotary element to define oil spaces, an oil supply to one end of the support, said support having openings therein to permit oil to pass into the said oil spaces, said engine having a crank case, and return means from one end of the rotary element support to the crank case.
- 10 15 20

W. FRED VALLIER.
